FEEDER CONTROL MECHANISM

Ralph M. Hardgrove, Westfield, N. J., assignor
to The Babcock & Wilcox Company, Newark,
N. J., a corporation of New Jersey

Application April 3, 1934, Serial No. 718,756

8 Claims. (Cl. 83—44)

The present invention relates in general to feeder control mechanisms, and more particularly to mechanisms of this type for controlling the supply of material to an endless bucket elevator. Such elevators are usually enclosed in a casing to confine the dusty atmosphere which usually exists about the moving buckets and belt or chain upon which they are mounted, and to return material spilled from the buckets to the bottom or boot of the elevator casing. The material to be elevated is supplied to the elevator casing boot where it is scooped up by the moving buckets as they pass about the lower chain sprocket wheel. As the buckets pass over the upper pulley of the elevator, the material is discharged by centrifugal force and gravity into an adjacent discharge chute. Economical elevator operation requires the supplying of material at a rate substantially corresponding to the bucket capacity. When that rate is exceeded the height of material in the boot tends to increase, causing an increase in load on the elevator driving means, increased wear, and overloading of the buckets with a resultant increase in the amount of material spilled from the buckets. I have discovered that the air pressure conditions in the elevator casing tend to fluctuate with changes in the amount of material spilled from the moving buckets and I advantageously employ such fluctuations in air pressure from a predetermined value to control the amount of material supplied to the elevator.

Elevators of the above described type are used extensively in closed circuit pulverizer systems to receive the discharge from a pulverizer and transfer the same to an elevated separator, from which the separated coarse material is returned to the pulverizer and the fines delivered to a storage system or point of use. The raw material is normally delivered to the pulverizer by a regulable feeder mechanism, which, when a constant speed pulverizer drive is used, may be regulated to vary the amount of material passing through the pulverizer. Grinding conditions in the pulverizer may change during operation, and cause the quality of the pulverized product to vary and the pulverizer drive motor to be overloaded or the elevator capacity to be exceeded. For a given material having a definite grindability, there is an optimum rate of feed and recirculation of material for the desired fineness. The general object of my invention is the provision of an elevator of the character described with an improved system of controlling the supply of material thereto. A further and more

specific object is the provision of an elevator feed control system operable in response to fluctuations in air pressure in the elevator casing. A further specific object is the provision of a material pulverizing system having provisions for controlling the supply of material to the pulverizer in response to the load on the pulverizer drive mechanism and/or on an elevator of the type described receiving pulverized material from the pulverizer.

The various features of novelty which characterize my invention are pointed out with particularity in the claims annexed to and forming a part of this specification. For a better understanding of the invention, its operating advantages and specific objects attained by its use, reference should be had to the accompanying drawing and descriptive matter in which I have illustrated and described a preferred embodiment of my invention.

Of the drawing:

Fig. 1 is a partly diagrammatic elevation of a closed-circuit pulverizer system incorporating my invention; and

Fig. 2 is a schematic diagram of the feeder control provisions.

In the closed-circuit grinding system illustrated in Fig. 1, raw material is discharged from a feed bin 10 to a suitable feeder 11 driven by a direct current shunt wound electric motor 12 in a well known manner. The raw material is discharged by the feeder at a rate dependent on the speed of the motor 12 into a pipe 13 leading to a pulverizer 14 of the gravity-discharge type. The pulverizer is preferably driven by a three phase constant speed electric motor 15 and the pulverized material discharged through an inclined conduit 16 into the boot of a vertical elevator casing 17. The casing 17 contains upper and lower sprocket wheels 18 and 19 respectively for driving an endless belt or chain 20 having a series of buckets 21 mounted thereon. The buckets are arranged to pick up material in the casing boot during their passage therethrough and carry the same upwardly. As the buckets pass over the upper sprocket wheel, the material therein is discharged by gravity and centrifugal force into a chute 22, which discharges into the upper end of a conical air separator 23. The fine and coarse particles of material are separated therein, the fines passing through the pipe 24 to a pump or conveyor 25, having a vent pipe 26, and delivered to a storage system or point of use, while the coarse particles or tailings are returned to the pulverizer through a spout 28. The

vent pipe 26 may be provided with a fan 45, discharging into a centrifugal separator 46, which causes any material in the vented air to return to the elevator casing through a pipe 47, and air 5 to exit through a vent 48. The material passing through the pulverizer thus consists not only of raw material but also of recirculated coarse material.

In normal operation, the air pressure within 10 the elevator casing 11 is usually a slight vacuum. Assuming an increase in the supply of material to the boot of the casing 11, then the amount of 15 granular material spilled in transit will correspondingly increase. The elevator being of substantial height and the material conveyed of a 20 relatively high density, the spilled material in falling exerts a dragging effect on the air in the upper portion of the casing and causes the air pressure in the lower part of the casing to build up correspondingly. I have discovered that the 25 fluctuations in air pressure in the elevator casing bear a definite relation to the amount of material accumulated in the casing boot such that these fluctuations can be used as a basis for controlling the pulverizer feeder motor 12.

It has been found desirable to employ a constant speed motor 15 for driving the pulverizer 14. Any increase in supply of material to the 30 pulverizer beyond the pulverizer capacity tends to overload the motor 15 and adversely affect the fineness ratio, and a supplementary control may advantageously be employed in conjunction with the elevator casing air pressure responsive control, by which supplementary control the supply 35 of material may be suitably decreased whenever the motor 15 tends to become overloaded.

One form of suitable control system is illustrated in Fig. 2. The air pressure control may comprise a suitable pressure responsive device 30 40 consisting of a liquid sealed floating bell 31, to the interior of which is connected an air pipe 32, opening through one side of the elevator casing, as shown in Fig. 1, slightly above the axis of the lower sprocket wheel 19. Above the bell 31 is mounted a counterweighted lever 33 pivoted at 34 and carrying a suitable mercury contact switch 35, which is closed when the lever 33 is raised. A connecting member 36 is mounted on the bell 31 for connecting the latter to and actuating the lever 33 on a change in air pressure in the elevator casing. In operation, the closing of switch 35 is used to short circuit a sector 37 of a rheostat 38 in the field 39 of the feeder motor 12 to thereby effect a predetermined decrease 50 in the motor speed and consequently in the amount of material delivered by the feeder 11. The decrease in the amount of material delivered to the pulverizer causes a decrease in the amount of material supplied to the elevator casing. The 55 air pressure in the lower part of the casing consequently falls, causing the bell 31 to drop and the switch 35 to open, restoring the previous operating conditions.

A corresponding controlling effect on the feeder 60 motor 12 may be effected on a predetermined increase in the load on the pulverizer drive motor 15. For this purpose an overload relay 40 is inserted in the power line 41 to the pulverizer motor 15. On a predetermined increase in the current 65 through the relay, the contacts 42 and 43 will be closed to short circuit the sector 31 of the field rheostat of the feeder motor 12, with the results as aforesaid. When the load on the pulverizer motor is decreased to its normal value, 70 the overload relay operates to allow the contacts

42 and 43 to open. A switch 44 is advantageously positioned in the control system to permit the controls being thrown out of operation.

While the two parts of the control system operate independently, and either may be used to 5 the exclusion of the other, the simultaneous use of the two forms of control means has been found to be preferable, so that the feeder is controlled not only in response to the load on the pulverizer drive motor 15, but also in response to the 10 amount of material delivered to the elevator.

While in accordance with the provisions of the statutes I have illustrated and described herein the best form of my invention now known to me, those skilled in the art will understand that 15 changes may be made in the form of the apparatus disclosed without departing from the spirit of the invention covered by my claims, and that certain features of my invention may sometimes be used to advantage without a corresponding use 20 of other features.

I claim:

1. In combination, an elevator casing having a material inlet at its lower end and a material outlet at its upper end, a feeder for supplying material to be delivered to said casing inlet, a motor for driving said feeder, an endless elevator having substantially vertical runs in said casing and having a series of buckets thereon arranged to pick up material in the lower end of 30 said casing and discharge it at the upper end of said casing, and means responsive to fluctuations in the air pressure in said casing due to changes in the amount of falling material therein for controlling the operation of said feeder 35 motor.

2. In combination, an elevator casing having a material inlet at its lower end and a material outlet at its upper end, a feeder for supplying material to be delivered to said casing inlet, a motor for driving said feeder, an endless elevator having substantially vertical runs in said casing and having a series of buckets thereon arranged to pick up material in the lower end of said casing and discharge it at the upper end of said casing, 40 an air conduit opening to said casing and responsive to fluctuations in air pressure in said casing due to changes in the amount of falling material, an air pressure responsive device connected to the lower portion of said casing, and 45 means actuated by said pressure responsive device for controlling the operation of said feeder motor.

3. A grinding system including a pulverizer, a feeder for supplying material to said pulverizer, 55 an elevator casing arranged to receive the discharge of material by gravity from said pulverizer, endless bucket elevator means, in said casing, arranged to mechanically raise material in said casing and means responsive to pressure changes in said casing for controlling the operation of said feeder.

4. A grinding system including a pulverizer, a feeder for supplying material to said pulverizer, a substantially vertical elevator casing arranged 65 to receive the discharge from said pulverizer, an endless bucket elevator in said casing, and a device responsive to pressure changes in said casing for controlling the speed of said feeder.

5. In a grinding system comprising a pulverizer, 70 a drive motor therefor, a feeder for supplying material to said pulverizer, a drive motor for said feeder, an elevator casing arranged to receive the material discharged by said pulverizer, and an endless elevator having oppositely moving verti- 75

cal runs in said casing and having a series of buckets thereon arranged to pick up material in the lower end of said casing and discharge said material at the upper end of said casing, means 5 for controlling the operation of said feeder motor, and means responsive to changes in the air pressure in said casing for actuating said feeder motor control means.

6. In a grinding system comprising a pulverizer, 10 a drive motor therefor, a feeder for supplying material to said pulverizer, a drive motor for said feeder, an elevator casing arranged to receive the material discharged by said pulverizer, and an endless elevator having oppositely moving vertical runs in said casing and having a series of buckets thereon arranged to pick up material in the lower end of said casing and discharge said material in the upper end of said casing, means 15 for controlling the operation of said feeder motor, means responsive to changes in load on said 20 pulverizer motor for actuating said feeder motor control means, and means responsive to changes

in the air pressure in said casing for actuating said feeder motor control means.

7. In combination, a casing, an endless bucket elevator in said casing, means for supplying material to said casing to be raised therein by said elevator, and means responsive to variations in the air pressure in said casing effected by changes in the amount of material falling from said elevator during operation for controlling the operation of said material supplying means. 5

8. In combination, a substantially vertical casing, means for supplying material to said casing, means for passing material through said casing and causing a variable supply of material to have a gravity drop in said casing, and means responsive to variations in the air pressure in the lower part of said casing effected by changes in the amount of descending material passing through said lower part of said casing for controlling the amount of material supplied to said 15 20 casing. 10
